UNITED STATES PATENT OFFICE.

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE.

CENTERING DEVICE AND EMERGENCY COUPLER SUPPORT.

Application filed May 20, 1922. Serial No. 562,505.

This invention relates to improvements in draft gear for railway cars and more particularly to an improved centering device and emergency coupler support.

5 The ends of freight cars are designed to act as end girders or trusses to resist the static and quiescent stresses. However, in certain classes of equipment, such as automobile cars with end doors, drop end gondola 10 cars and flat cars it is necessary to resist these stresses by having the end sill of sufficient strength, independent of the end of the car.

15 It is also desirable in the classes of equipment mentioned to have the floor as low as possible for loading and unloading and as the height of the coupler from the rail is established by the American Railroad Association as $34\frac{1}{2}$ " it is necessary in such equipment to sever or partially cut away the end sill at the center to permit the application of the coupler and the attached draft rig-

ging. 20 It has been found advantageous, therefore, to have the carry iron cast integral with the striking casting so as to obtain a four sided member which reinforces the end sill at the point where it is severed, and consequently weakened, as mentioned 25 above.

It has been found desirable to support 30 the coupler by what has been termed a swing motion carrier or some other means of coupler centering device so as to keep the coupler in the center of the car. This assures a proper coupling in service and transmits the blow of the impact directly through the coupler shank and to the draft gear without setting up lateral stresses in the coupler head or the coupler shank with its consequent damage to the coupler and parts.

The usual type of striking casting used 45 with swing motion carrier consists of a casting in the form of a yoke or inverted U with the two sides and top secured to the adjacent parts of the end sill and so arranged that the carrier swings between these two parts, the lower part of the yoke being open so that the coupler can be removed. 50 With such a yoke construction it is difficult to adequately tie the draft sills together to prevent their spreading and to cause them to resist lateral thrusts in unison. The swinging carrier permits a harder side blow 55 and has more tendency to spread the sills,

therefore, an integral tie at the bottom becomes essential.

The object of this invention is in the arrangement and combination of parts so as to obtain the advantages of the four sided 60 striking casting described and also the swing motion carrier described without reducing the efficiency of either.

Rigid and swing motion carrier are generally attached to the car by means of bolts 65 having nuts and cotters or by pins, which parts frequently become loose and lost, thereby permitting the carrier to fall causing the coupler to fall upon the track and frequently derailing the cars. It must be remembered that the rear end of the coupler is secured to the draft gear so that the coupler cannot merely fall upon the track and be run over by the car.

If the lower horizontal portion of the combined (integral) striking casting and coupler support fails the coupler is not permitted to fall because it is supported by the swing motion coupler support.

If any of the coupler supporting parts 70 fail in my arrangement the coupler does not fall but is supported by the lower portion of the four sided striking casting. The said lower portion may be termed an emergency or auxiliary carry iron, or coupler support. The swing motion carrier moves between the two walls of the emergency coupler support, whose upper surfaces are nearly on a level with the supporting surface of the swing motion carry iron. Therefore, in the event 75 of a breaking of any member of the centering device the coupler is only lowered a fraction of an inch before it rests upon the emergency coupler support. This is advantageous because the coupler is still within 80 the vertical limits prescribed by the interchange rules of the American Railroad Association and the car will be allowed to move to its destination without delay for repairs or transfer of the lading.

The lower horizontal portion of this striking casting is formed in a U section which gives it great compressive as well as tensile strength and also the upstanding legs 85 of the U form guides for the swing motion carry iron to restrict its longitudinal movement relative to the car.

While the preferred form of this invention is illustrated upon the accompanying 90 sheets of drawings, yet it is to be understood 95

that minor detail changes may be made without departing from the scope thereof.

In the drawings:

Fig. 1 shows a plan view on the right half 5 of the center line and on the left half a section on line 1—1 of Fig. 2 of my invention applied to a freight car.

Fig. 2 shows a front elevation of Fig. 1.

Fig. 3 shows a section on line 3—3 of 10 Fig. 2.

Fig. 4 shows a section on line 4—4 of Fig. 2.

Fig. 5 shows a perspective view of link.

Fig. 6 shows a perspective view of carrier. 15

In the drawings 1 is the vertical portion, 2 the horizontal portion of the end sill respectively, and 3, 4, and 5 are the top, side and bottom portions of the front wall of the striking casting or end frame member forming a four sided striking casting which surrounds the aperture for the car coupler 6. Rearwardly extending walls 7 and 8 stiffen the casting and form top and side buffing surfaces for the coupler and connect the 20 front and rear walls of the member. Horizontal wall 9 stiffens the casting and reinforces portion 2 of the end sill, while rear wall 10 and its extension 11 reinforce the end sill by transmitting end sill stresses from 25 one portion of the end sill to the other through the top portion of the striking casting formed by walls 3, 8 and 9 and through the bottom portion formed by walls 5, 12 and 13. It will be noted that both the bottom and top portions of the striking casting are capable of resisting either compression or tension, such members are "strut-ties," thus the casting rigidifies and stiffens this portion of the end of the car.

10 The coupler 6 rests upon carrier 14 positioned between the front and rear walls of the end frame member for protection. The carrier is swingingly supported at its ends by trunnion links 15 resting in journal seats 15 16 cast integral with the striking casting. The coupler bearing surface of the carrier 14 is positioned above the upper part of walls 5 and 13 of the emergency coupler support so that normally the coupler is out of 10 contact with walls 5 and 13 and is consequently free to freely move laterally of the car. However, in the preferred form, clearance would be allowed between the bottom of carrier 14 and the wall 12 to allow the 15 coupler to rest upon wall 5 or 13 in case of a failure of the carrier 14 or either of its supporting members.

10 Projections 17 keep the coupler in the center of the carrier 14. The carrier may swing freely laterally of the car but is restrained from moving longitudinally of the car by the walls 5 and 13 which are adjacent the sides of the carrier with sufficient room for clearance. Drain holes 18 are provided.

The interchange rules of the American Railway Association prescribe a limited permissible vertical movement of a car coupler so that it will adjust itself to the unevenness of the track and to the various heights 70 of the couplers from the rail. This vertical clearance is shown in Fig. 2. The various parts of my device are so positioned and dimensioned that the links 15 cannot be removed from their bearings 16 in the frame 75 member or from their bearings in the carrier 14 while the coupler is in its normal position on the carrier. This is accomplished by making the vertical depth of the recessed bearings 16 in the frame member and the 80 vertical depth of the recessed bearings in the carrier greater than the vertical distance between the coupler and the frame member.

After the coupler is removed it may be desirable to remove the carrier without removing either of the links from the frame member. This is accomplished by having the vertical clearance above the upper part of the carrier and the frame member greater than the vertical depth of the recessed bearings in the carrier. 85 90

In the embodiment of my invention illustrated the links 15 have the same T-head construction on each end and are symmetrical about their longitudinal and lateral axes. 95 With this type of link, therefore, it is impossible for the device to be improperly assembled. Furthermore, this double T-head link eliminates any bolts, pins or cotter which are always objectionable because of 100 their tendency to loosen and fall out. The ends of the carrier are bifurcated and provided with recessed bearings formed in the lower part of each bifurcated portion so as to form spaced apart recessed bearings to 105 accommodate the T-head link 15.

What I claim is:

1. The combination, in a railway car, of a coupler, a striking casting having an emergency coupler support cast integral therewith, and an independent carrier supported by swinging links to the side walls of said striking casting.

2. As an article of manufacture for a railway car, a striking casting having an emergency coupler support cast integral therewith, and arranged to accommodate swing motion links for a separate carrier.

3. The combination, in a railway car, of a coupler, a striking casting having an emergency coupler support cast integral therewith, and an independent coupler carrier supported by swinging links to the side walls of the striking casting having its coupler bearing surface positioned above 120 said emergency support.

4. The combination, in a railway car, of a car coupler, an end frame member restricting the upward movement of said coupler, a coupler carrier swingingly suspended from 130

- 5 said frame member by links, each link provided with a T-head at each end engaging bearings in said carrier and frame member respectively, said T-heads and bearings so positioned and dimensioned that the links cannot be removed before the coupler is removed.
- 10 5. The combination, in a railway car, of a coupler, a striking casting having an emergency coupler support cast integral therewith, and a coupler carrier supported by swinging links to the side walls of the striking casting, said support comprising means to restrict the movement of said carrier longitudinally of the car.
- 15 6. The combination, in a railway car, of a coupler, a striking casting having an emergency coupler support cast integral therewith, and a coupler carrier supported by swinging links to the side walls of the striking casting, said support comprising two parallel walls between which the carrier freely moves laterally of the car but is restricted in its movement longitudinally of the car.
- 20 7. The combination, in a railway car, of a car coupler, a member restricting the upward movement of said coupler, a coupler carrier having spaced apart recessed bearings in the lower part of each end, and links swingingly suspending said carrier from the car provided with T-heads at their lower ends to engage said bearings, the vertical depth of said recessed bearings being greater than the possible upward movement of said coupler when the device and coupler are assembled.
- 25 8. The combination, in a railway car, of a coupler, an end frame member, a coupler carrier swingingly suspended from said frame member, by links, each link provided with a T-head at each end engaging bearings in said carrier and frame member respectively, said T-heads and bearings so positioned and dimensioned that the links cannot be removed before the coupler is removed.
- 30 9. An article of manufacture, a suspension link for car coupler carriers having a T-head at each end, said link being symmetrical with respect to center lines across its width and length.
- 35 10. The combination, in a railway car, of a coupler, an end frame member restricting the upward movement of said coupler, a coupler carrier swingingly suspended from said frame member by links, each link provided with a T head at each end, engaging bearings in said carrier and frame member respectively, said T heads and bearings so positioned and dimensioned that neither of said links can be removed before the coupler is removed.
- 40 11. In a railway car, the combination of an end sill, two draft sills, an end frame member comprising a vertical rear wall secured to all of said sills and having an aperture for a coupler, a vertical front wall integrally connected to said rear wall and having an aperture for a coupler, a coupler carrier movably positioned between said walls, and means to keep the carrier in the longitudinal center of the car, comprising links swingingly suspending the opposite ends of said carrier to said frame member.
- 45 12. The combination in a railway car of a coupler, a striking casting having an emergency coupler support cast integral therewith, and an independent carrier supported by swinging links to said striking casting.
- 50 13. The combination in a railway car of a coupler, a striking casting having an emergency coupler support cast integral therewith, and an independent coupler carrier supported by swinging links to said striking casting having its coupler bearing surface positioned above said emergency support.
- 55 14. The combination in a railway car, of a coupler, a striking casting having an emergency coupler support cast integral therewith, and a coupler carrier supported by swinging links to said striking casting, said support comprising means to restrict the movement of said carrier longitudinally of the car.
- 60 15. The combination in a railway car, of a coupler, a striking casting having an emergency coupler support cast integral therewith, and a coupler carrier supported by swinging links to said striking casting, said support comprising two parallel walls between which the carrier freely moves laterally of the car but is restricted in its movement longitudinally of the car.
- 65 16. In combination with a railway car and a coupler having a shank, a carrier for the coupler shank, swinging links suspending the carrier, and a rigid confining structure for the coupler shank comprising a top member, spaced side members and a member extending between the lower ends of the side members and positioned to provide an emergency support for the carrier and coupler shank.
- 70 17. The combination in a railway car of a coupler, a striker having an emergency coupler support and an independent carrier supported by swinging links to said striker.
- 75 18. A coupler centering device comprising a striker plate presenting spaced side frames, a coupler carrier movable between said side frames, hooks supported adjacent said side frames, links suspended from said hooks and engaging said carrier to provide a swinging suspension means therefor and an emergency coupler support extending between the side frames and positioned to sustain said carrier upon failure of the links.
- 80 19. The combination in a railway car; a car part, a carrier supported by swingable

links to said car part, and an emergency carrier support integral with the car part.

20. The combination in a railway car; a car part, a carrier supported by swingable links to said car part, an emergency carrier support integral with the car part, and an emergency coupler support integral with the car part.

21. The combination in a railway car; a car part, a carrier supported by swingable links to said car part, an emergency carrier support integral with the car part, and an

emergency coupler support integral with the car part so positioned when the carrier is supported by its emergency support the coupler is supported by its emergency support independently of the carrier.

22. An article of manufacture for a railway car; a striking casting having an emergency carrier support cast integral therewith and arranged to accommodate swing motion links for a swingable carrier.

GARTH G. GILPIN.
